UNITED STATES PATENT OFFICE.

JOHN M. HASTING, OF OSKALOOSA, KANSAS.

WINDMILL WATER-ELEVATOR.

SPECIFICATION forming part of Letters Patent No. 237,527, dated February 8, 1881.

Application filed December 6, 1880. (No model.)

To all whom it may concern:

Be it known that I, JOHN M. HASTING, of Oskaloosa, in the county of Jefferson and State of Kansas, have invented a new and useful Improvement in Windmill Water-Elevators, of which the following is a specification.

Figure 1 is a sectional side elevation of the improvement. Fig. 2 is a sectional elevation of the weight-bucket.

10 Similar letters of reference indicate corresponding parts.

The object of this invention is to furnish windmill water-elevators so constructed that the water-elevators will be automatically 15 stopped and started to keep the receiving-trough always supplied with water.

The invention consists in the combination, with the trip-rod for throwing the wind-wheel out of the wind, of a tilting water-trough and 20 a valved bucket suspended on the trip-rod, substantially as hereinafter described, whereby the wind-wheel will be alternately thrown into or out of operation, according as the trough becomes empty or filled with water.

25 A represents the pump, and B the pump-rod, which is connected with and operated by a windmill, O, of any of the ordinary constructions.

C represents the trip-rod, by means of which 30 the wind-wheel P can be thrown out of the wind in the ordinary manner.

D is a spout leading from the pump-nozzle E to the water-receiving trough F. The trough F is pivoted at or near its center to a fulcrum-block, G, so that the said trough can tilt or rock longitudinally. The tilting of the trough F is limited by stop-blocks H I, placed beneath its ends, and which may be supplied with guide-pins passing into slots in the ends of 40 the trough F, to keep the said trough in place. The end of the trough F next the pump A is made deeper than the other end, to contain more water, so that when the trough is filled the said inner end will be forced downward by 45 the weight of the water. The outer end of the trough F is made with a thicker bottom, or is otherwise weighted, so that when the trough is emptied the said outer end will be forced downward by its weight.

50 To the lower end of the trip-rod C is attached a bucket, J, of such a size that when filled

with water its weight will draw down the trip cord or rod C with sufficient force to throw the wind-wheel P out of the wind. The bucket J has an aperture or opening in its bottom, which 55 is closed by a valve, K, the upper part of which rises above the top of the bucket J and is slotted longitudinally to receive the end of an arm, L, the other end of which is rigidly attached to the inner end of the trough F, so 60 that the valve K will be forced into and withdrawn from the aperture in the bottom of the bucket J by the tilting of the trough F.

In the lower part of the slot in the valve K is placed a spiral spring, M, the elasticity of 65 which holds the valve K in the aperture in the bottom of the bucket, when the said bucket is forced downward by being filled with water.

N is a spout, the outer end of which is connected with the upper part of the inner end of 70 the trough F, so that when the said trough becomes filled with water the water will overflow through the spout N. The inner end of the spout N is so placed that the water that flows through the said spout N will flow into 75 the bucket J.

With this construction, when the trough F becomes filled with water the weight of the water will tilt the inner end of the trough 80 downward till its said inner end rests upon the block H, which downward movement of the inner end of the trough F causes the arm L to compress the spring M and force the valve K into the aperture in the bottom of the bucket J, so that the water that 85 overflows through the spout N will fill the said bucket. As the bucket J fills with water the weight thus given to the bucket draws the trip-cord C downward and throws the wind-wheel P out of the wind, stopping the pump. 90 As the bucket J moves downward the elasticity of the spring M forces the valve K downward, and thus keeps it in place in the aperture in the bottom of the bucket J, so that the water cannot escape from the said bucket, and the 95 wind-wheel P is held out of the wind so long as enough water remains in the trough F to hold the inner end of the said trough down upon the block H. When so much water is taken from the trough F—by the drinking of 100 stock or otherwise—that the outer end of the said trough becomes the heavier, the said

trough is tilted outward, raising its inner end, which upward movement of the inner end of the said trough causes the arm L to withdraw the valve K from the aperture in the bottom 5 of the bucket J, allowing the water to flow out of the said bucket, so that the bucket will rise, and thus throw the wind-wheel P into the wind and again start the pump A. In this way the pump will be started and stopped 10 automatically, and the trough will be kept filled.

Having thus fully described my invention, I claim as new and desire to secure by Letters Patent—

15 1. In a windmill water-elevator, the combination, with the trip-rod C, of the vibrating trough F and the valved bucket J, substantially as herein shown and described, whereby the water-elevator is started and stopped au- 20 tomatically, as set forth.

2. In a windmill water-elevator, the combination, with the tilting trough F and the bucket J, having aperture in its bottom, of the arm L, the valve K, and the spout N, substantially as herein shown and described, whereby 25 the valve in the bucket is opened and closed by the tilting of the trough, as set forth.

3. In a windmill water-elevator, the combination, with the valve K and the arm L, of the spring M, substantially as herein shown 30 and described, whereby the valve is held in place while the bucket is moving downward, as set forth.

JOHN MOOR HASTING.
